US0D1093781S

(12) **United States Design Patent** (10) **Patent No.:** **US D1,093,781 S**
(45) **Date of Patent:** **** Sep. 16, 2025**

(54) **VACUUM CLEANER**

(71) Applicant: **Zhejiang Prulde Electric Appliance Co., Ltd.**, Zhejiang (CN)

(72) Inventor: **Chenghao Yang**, Zhejiang (CN)

(73) Assignee: **Zhejiang Prulde Electric Appliance Co., Ltd.**, Zhejiang (CN)

(**) Term: **15 Years**

(21) Appl. No.: **29/926,461**

(22) Filed: **Jan. 30, 2024**

(30) **Foreign Application Priority Data**

Sep. 27, 2023 (CN) 202330633865.1

(51) **LOC (15) Cl.** **15-05**

(52) **U.S. Cl.**

USPC **D32/18**

(58) **Field of Classification Search**

USPC D15/199; D21/526, 578; D32/15, 17, D32/18, 21, 24, 38

CPC A47L 5/00; A47L 5/12; A47L 7/00; A47L 7/0076; A47L 11/00; A47L 11/22; A47L 11/24; A47L 11/32; A47L 11/33

(57) **CLAIM**

The ornamental design for a vacuum cleaner as shown and described.

DESCRIPTION

FIG. 1 is a perspective view of a vacuum cleaner showing my new design;

FIG. 2 is a front view of thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in FIGS. 1-7 illustrate portions of the vacuum cleaner that form no part of the claimed design.

1 Claim, 7 Drawing Sheets
